UNITED STATES PATENT OFFICE.

EMILIO PROVENZANO, OF PHILADELPHIA, PENNSYLVANIA.

TIME-CONTROLLED PHONOGRAPH STARTING DEVICE.

Application filed May 10, 1923. Serial No. 637,979.

To all whom it may concern:

Be it known that I, EMILIO PROVENZANO, a subject of the King of Italy (having declared his intention of becoming a citizen of the United States), residing at Philadelphia, in the county of Philadelphia and State of Pennsylvania, have invented certain new and useful Improvements in Time-Controlled Phonograph Starting Devices, 10 of which the following is a specification.

My invention relates to time-controlled phonograph starting devices and its object is to provide such a device which will fit any size phonograph, may be easily applied, 15 will not interfere with the regular playing of the phonograph and which is of simple and durable construction.

This object, and other advantageous ends which will be described hereinafter, I attain 20 in the following manner, reference being had to the accompanying drawings in which—

Figure 1 is a plan view of a phonograph having my invention applied thereto,

25 Figure 2 an inverted sectional plan view of Figure 1, illustrating the under side of my invention, and

Figure 3 an enlarged section taken substantially on line 3—3 of Figure 1, the 30 phonograph being omitted.

Referring to the drawings, 1 is a phonograph cabinet, 2 the turntable, 3 the stopping lever, 4 the tone arm and 5 the tone arm supporting base. My invention includes a frame 6 stamped from sheet metal and preferably of the form shown. The frame is provided with extensions 7, 8 and 9 formed to provide guideways 10 for receiving securing arms 11, 12 and 13 respectively. Set screws 14 on the extensions secure the arms in position. The arm 11 engages the base of the tone arm and the arms 12 and 13 engage the cabinet. The ends of the arms are preferably provided 45 with felt or other like material so that the parts which the securing arms engage will not be marred. The frame is supported on the cabinet by downwardly bent legs 15. Standards 16 and 16^a, integral with the 50 frame, receive an alarm clock 17. Standards 16^a are provided with notches 18 which receive clock-supporting legs 19 and thereby prevent turning of the clock. A plunger supporting arm 20 is integral with the 55 frame and extends toward the stopping lever 3. The end of the arm is bent down-

ward to provide a stopping leg 21 which serves to slidably receive a plunger 22 which has one end 23 engaging the stopping lever 3. The other end 24 is pivotally connected 60 to an actuating link 25 which is pivoted to the frame at 26. An idler link 27 is pivoted to the frame at 28. A connecting bar 29 pivotally connects the ends of the links at 30 and is provided with a lug 31 adapted to 65 engage and be actuated by a winding lever 32 on the alarm winding stem 33 of alarm clock 17. A spring 34 is connected to the frame and the lug and serves to return the movable parts into their normal position. 70

To apply my invention to a phonograph, the frame is placed with its legs 15 resting on the top board 35, and the arms 11, 12 and 13 moved until they engage the tone arm base and the sides of the cabinet respectively. The frame is adjusted so that the end 23 of the plunger will barely touch the stopping lever. The arms are then secured to the extensions by tightening the set screws 14. 75

To use my invention, the alarm clock is wound by the winding lever 32 in the usual manner and the alarm set for the desired time. The clock is then placed between the standards so that its legs 19 will be within 80 the notches 18 of the standards 16^a and the winding lever substantially in the position shown in Figure 2, engaging the lug 31 or nearly so. The sound box and tone arm are put in position on the record ready for playing. When the alarm is set off the winding lever will turn in the opposite direction to that when it was wound as shown by the arrow in Figure 2 and move the lug 31 which causes the plunger 22 to move the 85 stopping lever 3 and release the turntable 2 as shown in dot-and-dash lines in Figure 2. The turntable will then start to rotate and the record will be played. After the movable parts have reached the position shown in dot-and-dash lines in Figure 2 the spring 34 will return them to their normal 90 position and the winding lever 32 will move around until it engages a stop 36 integral with the frame. By constructing a time-controlled phonograph stopping device as above described the phonograph may be played in the regular way without interference by the device. The device will fit any size machine, it being merely necessary 100 to adjust the arms 11, 12 and 13. 105

By providing simple parts which are

easily stamped from sheet metal, the device is produced at a low cost.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patents is:—

1. In combination with the winding lever of an alarm clock and the stopping lever of a phonograph; a frame for horizontally supporting the clock; a plunger horizontally movable in the frame adapted to move the stopping lever, and means on the frame actuated by the winding lever to move the plunger.

2. In combination with the winding lever of an alarm clock and the stopping lever of a phonograph; a frame for receiving the clock; means for horizontally supporting the frame; a horizontally movable plunger adapted to move the stopping lever; a link pivoted on the frame and pivotally connected to the plunger, and means actuated by the winding lever to move the link.

3. In combination with the winding lever of an alarm clock and the stopping lever of a phonograph; a frame for receiving the clock; means for horizontally supporting the frame; a plunger for moving the stopping lever; an actuating link pivoted to the frame and pivotally connected to the plunger; an idler link pivoted to the frame; a connecting bar pivotally connected to the links and provided with a lug adapted to be moved in one direction by the winding lever, and a spring for moving the lug in the opposite direction.

4. In combination with the winding lever of an alarm clock and the stopping lever of a phonograph; a frame provided with a plunger supporting arm, supporting legs and clock-supporting standards; means for securing the frame to the phonograph; a plunger slidable in the plunger arm and adapted to engage the stopping lever, and means actuated by the winding lever to move the plunger.

5. In combination with the winding lever of an alarm clock and the stopping lever

of a phonograph; a frame provided with a plunger supporting arm, supporting legs and clock-supporting standards, certain of the standards being provided with notches for receiving parts of the clock; means for securing the frame to the phonograph; a plunger slidable in the plunger arm and adapted to engage the stopping lever, and means actuated by the winding lever to move the plunger.

6. In combination with the winding lever of an alarm clock and the stopping lever of a phonograph; a frame provided with a plunger supporting arm, supporting legs, clock-supporting standards and extensions; securing arms slidable in the extensions and adapted to engage parts of the phonograph; means for securing the arms to the extensions; a plunger slidable in the plunger arm and adapted to move the stopping lever, and means actuated by the winding lever to move the plunger.

7. In combination with the winding lever of an alarm clock and the stopping lever of a phonograph having a tone arm and a cabinet; a frame provided with a plunger supporting arm, supporting legs, clock-supporting standards and extensions; securing arms slidable in the extensions, one of the arms being adapted to engage the tone arm base, and the others the cabinet; means for securing the arms to the extensions; a plunger slidable in the plunger arm and adapted to engage the stopping lever, and means actuated by the winding lever to move the plunger.

8. A time-controlled phonograph starting device including a frame provided with extensions; securing arms slidable in the extensions and adapted to engage the phonograph, and means for securing the arms to the extensions.

9. A time-controlled phonograph starting device including a frame provided with extensions; securing arms slidable in the extensions, one of the arms being adapted to engage the phonograph tone arm base and the others the phonograph cabinet, and means for securing the arms to the extension.

In testimony whereof I have signed my name to this specification in the presence of two subscribing witnesses.

EMILIO PROVENZANO.
